GAS ESCAPE REACTION PROPULSION DEVICE

Alexander C. Hutchison and Matthew Wilson,
 Saltcoats, Scotland, assignors to Imperial
 Chemical Industries Limited, a corporation of
 Great Britain

Application January 28, 1949, Serial No. 73,364
 In Great Britain March 3, 1948

8 Claims. (CL. 60—35.6)

1

The present invention relates to the provision of an improved gas escape reaction propulsion device.

The invention has for an object to provide a simple, safe and efficient self-contained gas escape reaction propulsion device containing a solid charge of a thermally actuatable hot gas generating composition within a casing having a perforated wall element providing a gas vent to the exterior that will maintain an internal pressure and retain its predetermined dimensions until the charge is consumed, by means of which there may be propelled a toy, model or the like to which it is attached.

It is well known that rockets can be used for propulsion purposes. For the propulsion of toys and models, however, the conventional firework rockets are less efficient than is desirable owing to their high yield of solid combustion products from blackpowder and like compositions tending to clog narrow orifices, and because of the high rate of combustion index and consequent liability of such compositions to explode when the gases are allowed to rise appreciably in pressure before they escape. Consequently, the thrust it is possible to maintain on the toy or model is undesirably limited. They are also unsuitable for use indoors. The flames and sparks emitted by conventional firework rockets and their ready ignitability also entail a certain risk of personal injury to the operator, especially a juvenile operator, who may have at hand several rockets at a time in order to despatch his toy or model on successive journeys. Moreover the firework character of conventional rockets renders their packing, storage and transport in bulk somewhat inconvenient and expensive.

According to the present invention an improved self-contained gas escape reaction propulsion device for a toy, model or the like comprises a cylindrical casing of heat insulating material closed at one end and provided with a compressed compact charge comprising a mixture of guanidine nitrate and/or nitroguanidine and a solid sensitizer of the thermal decomposition thereof in amount sufficient to enable the mixture to propagate through itself a self-sustained exothermic gas-producing non-explosive decomposition when a small amount of heat is locally applied at the terminal surface of said charge at atmospheric pressure, which terminal surface is spaced by an air space from a terminal wall element of heat resisting rigid material perforated with one or more pressure controlling gas escape holes of predetermined dimensions.

2

The said compressed compact charge if desired may be formed in situ in said cylindrical casing. On the other hand the said compressed compact charge may consist of a preformed pellet of a width to form a tight fit in said cylindrical casing.

The cylindrical casing may comprise a single tube capable of being provided with a turnover fold at each end or may comprise two telescopically closely fitting tubes one well inside the other and adhesively bonded together, each tube having a turnover fold at its free end.

In accordance with a preferred form of the invention, a portion of the insulating material of the cylindrical casing wall not in contact with said charge is deformable under a predetermined pressure in excess of the desired working gas pressure to establish an alternative gas escape exit to the exterior should the effective gas venting area in the terminal wall element become substantially reduced by clogging.

In the case of guanidine nitrate the sensitizer of its thermal decomposition may be for instance a polynitrophenol or a polynitrosophenol for example 2:4 dinitroresorcinol, 2:4 dinitrosoresorcinol, 2:6 dinitroparacresol in amounts ranging from about 8-20% of the weight of the guanidine nitrate. It is desirable to include preferably not more than 1 percent of vanadium pentoxide. An aliphatic acid selected from the group consisting of tartaric, citric, fumaric and maleic acids may be employed in partial replacement, or even in amounts ranging from about 20-30% in complete substitution of the polynitrophenol or polynitrosophenol. There may also advantageously be present in the composition preferably not more than one percent of asbestos fibre which increases the available power by assisting the decomposition, and if desired also preferably not more than 0.5 percent of potassium nitrate which assists the ignitability. Charges based on mixtures of guanidine nitrate and polynitrophenols or polynitrosophenols are claimed in co-pending application Ser. No. 42,948. Other sensitizers that may be used in the case of guanidine nitrate include for instance, chromates, dichromates and polychromates of alkali metals or ammonium; nitrocellulose; ammonium molybdate or molybdate acid with asbestos, or cuprous chloride or cupric oxide in amounts ranging from about 3 to 12%. In the case of nitroguanidine, chromates, dichromates or polychromates of the alkali metals or ammonium may be used.

When required, local heating means is introduced through a controlling gas escape hole by

the operator and may consist for instance of a length of fuse or match composition in the form of a thread or mounted on a wire, the protruding portion of which is then lit. The local heating means may also take the form of a length of wire or the like that has been heated for instance in a domestic fire, gas flame or even match flame. It will be appreciated that the device as marketed does not have exposed fuse or like means of ignition. The gases generated by the decomposition of the sensitized guanidine nitrate or nitroguanidine composition are usually accompanied by little or no flame as they escape through a venting hole or holes. The terminal wall element may be made of temperature resisting metal construction, e. g. tinplate, aluminium alloys, nickel, stainless steel, non-porous refractory materials like silica, porcelain or compressed asbestos sheets. Since the devices as marketed are free from exposed fuse or like means of ignition they are particularly safe for children to handle.

The insulating material of the cylindrical casing wall not in contact with the charge may have a weakened portion that will burst open when a predetermined pressure in excess of the working pressure is attained, but since in affixing the terminal wall element to the insulating material forming said wall the latter must be deformed, for instance, by turning its end over the rigid terminal wall element, it is convenient to arrange to form the cylindrical casing wall of such material that this turnover fold will unfold itself if a predetermined pressure in excess of the desired working pressure should be developed within the device, this predetermined pressure being low enough to ensure that an emergency gas escape exit will thus be established before any danger of the charge decomposing in an explosive manner could arise.

An embodiment of the invention is illustrated in the diagrammatic drawings accompanying the specification whereof Fig. 1 represents on an increased scale a longitudinal axial section and Fig. 2 an end plan of a device suitable for the driving of a toy vehicle.

In the diagrammatic drawings 1 is a cardboard cylinder turned over a thick cardboard disc 2 as shown at 6, 8 is the main gas producing charge of a composition consisting for instance of a mixture of:

Percent by weight

Guanidine nitrate	91.0
2:4 dinitroresorcinol	8.0
Asbestos fibre	0.3
Vanadium pentoxide	0.5
Potassium nitrate	0.2

strongly compressed into the resulting container wall whereof the base and sides are supported in the press. 3 is a small charge of ignition composition consisting for instance of 2:4 dinitroresorcinol. Into the open end of the container a tinplate disc 4, which is provided with a cylindrical hole 5 of a diameter approximately one-tenth of that of the disc, is forced for a short distance, and the end of the wall 1 extending beyond the disc 4 is turned over as shown at 7. The internal diameter of the device is 1.9 cm. and the weight of the charge 8 is 8 grams and that of the charge 3 is 0.1 gram, their combined length being approximately 2.1 cm. and the space between the end of the charge 3 and the terminal disc 4 being approximately 0.75 cm. The diameter of the orifice is 0.19 cm. The external

diameter of the device is 2.05 cm. and the turnover at the forward end of the device unfolds if an internal pressure exceeding 5 atmospheres is built up. After the ignition has been brought about by means of a hot wire introduced through the hole 5, the steady working pressure in the space between the charge 8 and the disc 4 is 3 atmospheres; and the thrust delivered as the gases escape through the hole 5 is 28 grams weight and the time for which this is maintained is 15 seconds.

Another embodiment of the invention is illustrated in the diagrammatic drawings attached hereto whereof Fig. 3 represents on an increased scale a longitudinal axial section and Fig. 4 an end view of a device suitable for the driving of a toy vehicle.

In the diagrammatic drawings 9 is a cardboard cylinder turned over a thick cardboard disc 10 as shown at 11 and telescopically fitting into and adhesively bonded to another cardboard cylinder 12 turned over a tinplate disc 13 as shown at 14. The disc 13 is supported at the end 15 of the inner cardboard cylinder 9. The tinplate disc 13 is provided with a cylindrical hole 16 of a diameter approximately one-tenth of that of the disc. The inner and outer cylinders have each a length of 3.8 cms. The internal diameter of the inner cylinder 9 is 1.9 cm. and the external diameter of the outer cylinder 12 is 2.05 cm. The diameter of the orifice is 0.19 cm. 17 is a preformed gas-producing pellet closely fitting in the inner cylinder 9 and is of the same composition and weight as 8 of Fig. 1. 18 is a piece of wire gauze fitting tightly in the inner cylinder and placed over a wick or igniting fuse 19 one end of which is bent over said gauze. The combined length of the pellet 17, gauze 18 and wick 19 is approximately 2.1 cm. and the space between the end of the charge 17 and the terminal disc 13 is approximately 0.75 cm. The turnover at 14 unfolds if an internal pressure exceeding 5 atmospheres is built up. The ignition of the bent over portion of the wick 19 can be brought about by inserting another length of wick through the jet and igniting the protruding portion when required. The ignited wick 19 ignites the pellet charge 17 and a steady working pressure of 3 atmospheres is attained in the space between the pellet charge 17 and the disc 13. The thrust delivered as the gases escape through the hole 16 is 28 grams weight and the time for which it is maintained is 15 seconds.

The device according to this embodiment of the invention is very easily assembled. The cylinders 9 and 12 are each provided with a turned over end 11 and 14 respectively. The cardboard disc 10 is pushed into cylinder 9 against the turned over end 11. The preformed pellet 17 is pushed down into cylinder 9 against the cardboard disc 10. The wick 19 is then placed on the preformed pellet 17 and the metal gauze 18 is placed over the wick 19 arranging that a portion of the wick 19 is bent over the gauze 18. The tin-plate disc 13 is inserted into the cylinder 12, the exterior surface of the cylinder 9 is coated with an adhesive composition and the cylinder 9 is then pushed into the cylinder 12 so that its rim 15 pushes the tin-plate 13 well up against the turned over end 14 of the outer cylinder 12.

We claim:

- An improved self-contained gas escape reaction propulsion device for a toy, model or the like comprising a cylindrical casing of heat insulating material and a compressed, compact

gas-generating charge in intimate contact with the cylindrical wall of said casing, said casing being closed at one end and provided at the other with a terminal wall element of heat resisting rigid material perforated to provide at least one pressure-controlling gas escape hole of predetermined dimensions, said compacted charge being of such length with respect to the casing as to leave an air space between a terminal surface of the charge and said terminal wall element, said cylindrical casing wall not in contact with the charge being deformable along a weakened portion which allows said casing to burst open under a predetermined pressure in excess of the desired working pressure, said compacted charge comprising in admixture a predominant proportion of a compound selected from the group consisting of guanidine nitrate, nitroguanidine and mixtures thereof, and a minor proportion of a solid sensitizer of the thermal decomposition of said compound in amount sufficient to enable the mixture to propagate through itself a self-sustained, exothermic, gas-producing, non-explosive decomposition at atmospheric pressure when a small amount of heat is locally applied at said terminal surface of said compacted charge.

2. An improved self-contained gas escape reaction propulsion device as claimed in claim 1, wherein the weakened portion of said casing consists of a turnover fold of said insulating material which is capable of being unfolded by a predetermined pressure in excess of the desired working pressure within the device.

3. An improved self-contained gas escape reaction propulsion device as claimed in claim 1, wherein the cylindrical casing comprises a single tube provided with a turnover fold at each end.

4. An improved self-contained gas escape reaction propulsion device as claimed in claim 1, wherein the cylindrical casing comprises two telescoped closely fitting tubes adhesively bonded together, each of said tubes having a turnover fold at its free end.

5. An improved self-contained gas escape reaction propulsion device as claimed in claim 1, wherein said charge comprises guanidine nitrate and said sensitizer is a derivative of phenol containing a plurality of substituent groups each consisting of a nitrogen atom attached exclusive to at least one terminal oxygen atom and to one of the nuclear carbon atoms of phenol, said sensitizer being present in substantial amount not exceeding about 20% of the weight of the guanidine nitrate.

6. An improved self-contained gas escape reaction propulsion device as claimed in claim 5, wherein said phenol derivative comprises 8 to 20% of the weight of the guanidine nitrate.

7. An improved self-contained gas escape reaction propulsion device as claimed in claim 5, wherein the phenol derivative is 2:4 dinitroresorcinol.

8. An improved self-contained gas escape reaction propulsion device as claimed in claim 5, wherein the phenol derivative is 2:4 dinitroresorcinol.
